(57) **CLAIM**

The ornamental design for a video conference system endpoint, as shown and described.

DESCRIPTION

FIG. 1 is a front elevational view of a video conference system endpoint showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a front, top and right side perspective view thereof;

FIG. 8 is a rear, bottom and left side perspective view thereof;

FIG. 9 is a rear, top and right side perspective view thereof;

FIG. 10 is an enlarged view of portion 10 in FIG. 1;

FIG. 11 is an enlarged view of portion 11 in FIG. 1;

FIG. 12 is an enlarged view of portion 12 in FIG. 7; and,

FIG. 13 is an enlarged view of portion 13 in FIG. 9.

The evenly spaced dashed broken lines depict portions of the video conference system endpoint that form no part of the claimed design. The dot-dot-dash line shapes depict the limits of the enlarged views and form no part of the claimed design.

1 Claim, 12 Drawing Sheets
